UNITED STATES PATENT OFFICE.

GEORGE E. MARTIN, OF PHILADELPHIA, PENNSYLVANIA, ASSIGNOR TO THE PEDRICK & AYER COMPANY, OF PHILADELPHIA, PENNSYLVANIA.

RIVETING-MACHINE.

SPECIFICATION forming part of Letters Patent No. 718,365, dated January 13, 1903.

Application filed December 21, 1901. Serial No. 36,734. (No model.)

To all whom it may concern:

Be it known that I, GEORGE E. MARTIN, a citizen of the United States, residing at Philadelphia, in the county of Philadelphia and 5 State of Pennsylvania, have invented certain new and useful Improvements in Riveting-Machines, of which the following is a specification, reference being had therein to the accompanying drawings.

This invention relates to pneumatic riveting-machines in which the force that operates the riveting devices is transmitted from the power-cylinder through a liquid medium.

In order that the invention may be readily understood, I will first describe the operation of the same and refer incidentally to the parts and detailed construction of the machine illustrated in the accompanying drawings, and subsequently will point out in the appended claims the novel characteristics of the invention.

In Figures 1 and 2 the machine is shown in side elevation, partly in section, with the principal elements composing the operative parts 25 in relative position, respectively, at the commencement and termination of operation. Fig. 3 is an exterior side view of the power-cylinder detached from the frame by broken lines and showing the operating-lever of the 30 air admission and exhaust valve, and the passages and pipes communicating therewith shown partly in dotted lines. Fig. 4 is a front elevation, partly in section, of the cylinder containing the dolly-bar and piston and a connected auxiliary cylinder containing a floating piston. Fig. 5 is a plan view of the base of the frame with the power-cylinder detached and showing the relative position of the cylinders C³ C⁴, Fig. 4. Fig. 6 represents an enlarged view, partly in section, of a relief-valve that controls a passage leading from the dashpot provided at the forward end of the power-cylinder. Fig. 7 is an enlarged end view, partly in section, of the bonnet or cover of the 45 power-cylinder containing the air-admission valve and connected ports and passages; and Fig. 8 is an enlarged central longitudinal section of the power cylinder and piston and air-admission valve. Fig. 9 is an enlarged sectional elevation of the cylinder containing the dolly-bar and piston with communicating

ports and passages, the relative position of the parts indicating the preliminary contact of the riveting-tools with the rivet.

Referring to Fig. 1 of the drawings, the parts 55 are shown relatively in starting position, air under compression being admitted to the valve-chamber 1 through the inlet-pipe x, the valve 2 being set to allow the air to pass through the open port 3 into passages 4 and 60 5 and annular space a and act upon the piston P and force it to the inner end of the cylinder C. At the same time the air is also admitted through the pipe 6 into the annular space 8 in the cylinder C⁴ of the dolly-bar R, 65 thereby forcing the dolly-bar piston P² to its extreme open throw. The air-admission valve 2 is now moved by the operating-handle H in direction to register the port 3 with the exhaust-port 13 to permit the air-pressure to escape 70 from the annular space a in the power-cylinder and from the annular space 8 in the dolly-bar cylinder C⁴. In this movement of the valve 2 the port 14 is first opened and the air under light pressure is admitted to passages 17, 18, 75 19, and 20, Figs. 3 and 7, and through pipe 21 and passages 22 and 23, Fig. 1, into the space 15 of the auxiliary cylinder C³, Fig. 4. The piston 16 in the auxiliary cylinder C³ is moved forward under this light pressure, and 80 the liquid in the cylinder C³ is forced through the port 24, Fig. 4, and passages 25, Fig. 9, and past the check-valve 26 into and filling the chambers 27 and 28, Figs. 8 and 9, and moving the dolly-bar piston P² to the position 85 shown in Fig. 9, which brings the dolly-rod R and riveting-die D in contact with the shank of the rivet 12, as shown. During this primary movement of the dolly-bar the air-pressure is excluded from the power-piston 90 P. Upon a further movement of the air-admission valve 2 port 30, Fig. 1, is opened and pressure admitted through passage 31 to the piston P in the power-cylinder, which upon starting intensifies the liquid-pressure in the 95 chambers 27 and 28 by the displacement of the hollow fixed spindle P' in the chamber 28 and closes the check-valve 26, Fig. 2. The continued movement of the power-piston upon the hollow fixed spindle P' forces the 100 liquid in chamber 28 through the spindle, producing an intensified pressure in the

chamber 27 by the increasing displacement of the spindle P' in chamber 28, which acts upon the piston P² and forces the dolly-bar R and riveting-die D to act upon and form the rivet-head under great and increasing pressure, as shown in Fig. 2. In the return movement of the piston P² and to insure its complete movement by the relief of all the liquid contained in the chambers 27 and 28 the stem of the check-valve 26 is connected with a small piston 34, fitted within a recess made in the end plug 35 of the dolly-bar cylinder. (See Fig. 9.) Upon the return of the parts, as shown in Figs. 1 and 4, wherein the air-pressure is admitted to the annular space 8, it is also admitted through the passages 36, 37, and 38, beneath the piston 34, Fig. 9, which forces the check-valve 26 to open and permit the superfluous liquid in the chamber 27 to return through the passages 25 and 24, Figs. 9 and 4, to the auxiliary cylinder C³. This auxiliary cylinder C³ is provided with a plug 39 for purpose of refilling the same.

In the head of the power-cylinder a chamber or recess 40 is provided to act in connection with the projecting part 41 of the power-piston for checking the return movement of the piston near the termination of the stroke, a relief-valve 42 (shown in the enlarged and detached view, Fig. 6, and end view, Fig. 7) being provided to permit the power-piston to fully complete its return stroke and to admit a small amount of air in the chamber or recess during the beginning of the forward stroke of the power-piston P. This device is well known in this class of machines and is not claimed herein.

The power-piston is constructed with an annular ring P and hollow trunk T of less diameter than the power-cylinder, which provides for the surrounding annular space a and the correspondingly-diminished effective piston area exposed to the operating pressure during its return movement, whereby an economy is obtained in the less quantity of air used. This hollow trunk portion T has

an interior chamber 23 for holding the liquid-transmitting medium and is provided at its head 32 with an opening and stuffing-box 33, by which the trunk T moves upon the fixed 50 hollow spindle P'.

In Figs. 1 and 2 the machine is shown in an inverted position with respect to the work to be performed for convenient use in particular places and in order to place the rivet 55 through the plates from above and prevent it from dropping out before the riveting-die is brought in contact. The machine, however, may be suspended by either of the respective bails shown and employed in the reverse position when desired.

What I claim, and desire to secure by Letters Patent, is—

1. In a riveting-machine, the combination of a power-cylinder provided with a differential power-piston constructed with a hollow trunk for containing a liquid, a fixed hollow spindle communicating therewith and with the riveting piston-cylinder; a minor piston-cylinder communicating independently with 70 the air-pressure and with the riveting-cylinder, and a check-valve device with means for operating the same located between the riveting and the minor cylinder, for the purpose set forth.

2. In a riveting-machine substantially as described, the combination of a riveting piston-cylinder C⁴, and a minor cylinder and piston C³ with the check-valve 26, connected piston 34, and communicating passages 36, 80 37, 38, whereby said check-valve 26 is opened upon the admission of the operating air-pressure to the valve-piston 34 to permit the contained liquid in the chamber 27 to pass to the minor cylinder C³ through passages 24, 25, 85 75 39, for the purpose set forth.

In testimony whereof I affix my signature in presence of two witnesses.

GEORGE E. MARTIN.
